JOHN R. SHEA, OF MAPLEWOOD, NEW JERSEY, ASSIGNOR TO WESTERN ELECTRIC COMPANY, INCORPORATED, OF NEW YORK, N. Y., A CORPORATION OF NEW YORK

APPARATUS FOR WORKING MATERIAL

Application filed February 10, 1931. Serial No. 514,718.

This invention relates to methods of and apparatus for working material, and more particularly to methods of and apparatus for serving material upon cores.

Objects of the invention are to provide improved methods of and apparatus for working material, whereby improved products may be produced efficiently and at higher speeds than heretofore practicable.

The invention contemplates the provision of a method of and apparatus for working material wherein the material being worked is subjected to controlled atmospheric conditions, such as pressure, humidity, temperature, etc., whereby any retarding or deleterious effects of the atmosphere are eliminated or reduced to a minimum. In one embodiment of the invention, the serving mechanism of an apparatus for serving textile or paper insulation on wire is enclosed in a vacuum chamber, whereby breakages of the serving material due to atmospheric friction are eliminated, thus permitting the safe and efficient operation of such apparatus at speeds considerably higher than heretofore practicable.

Other objects and advantages of the invention will become apparent from the following detailed description, when taken in conjunction with the accompanying drawing, in which

Fig. 1 is a fragmentary elevational view of an apparatus for applying paper ribbon insulation on wire in accordance with the present invention; and

Fig. 2 is a vertical section on line 2—2 of Fig. 1.

As shown in the drawing, a tubular vertical shaft 10 is rotatably journaled in a supporting base 11 and has a driving pulley 12 keyed thereto by means of which it is driven from any suitable source of power (not shown). Carried upon the upper end of the shaft 10 and driven thereby is a paper ribbon serving mechanism 15 of any well known type comprising a disk 16 for sup-

porting a pad of paper ribbon 17 and suitable paper tensioning mechanism 18. A serving mechanism of this type is fully illustrated and described in the patent to H. J. Boe, No. 1,405,710, issued February 7, 1922, and since it does not form a part of the present invention, further description thereof is believed unnecessary. It is believed sufficient to herein state that as a wire 20 drawn from a supply (not shown) is advanced by a capstan 21 through the tubular shaft 10 and serving mechanism 15, the paper ribbon is spirally wrapped thereon through the rotation of the serving mechanism, the angle of application of the paper on the wire being determined by the location of a polisher 22 with respect to the serving mechanism.

In apparatuses of the above and similar types, the speed of application of paper or other covering material has heretofore been limited by the large number of breakages of the material caused by the atmospheric friction encountered by the rotating serving mechanism as well as the material being served. Since each such break necessitates stopping and re-starting the apparatus, it is obvious that the efficiency of the apparatus decreases as the number of breakages increases, and thus the speed at which such apparatus could be operated efficiently has heretofore been limited.

The above speed limiting conditions are obviated by the method and apparatus of the present invention. This is accomplished by enclosing the serving mechanism, as well as the material being served, in a vacuum or partial vacuum, whereby atmospheric friction and the breakages resulting therefrom are eliminated or reduced to a minimum, thus permitting efficient operating speeds considerably higher than heretofore practicable. Furthermore, by reducing the number of breakages of the covering material, an improved and more uniform product is produced.

In the embodiment of the invention illustrated in the drawing, a cylindrical casing or hood 24 cooperates with the base 11, on which it is removably supported, to completely enclose the paper serving mechanism 15 as well as the paper being served. A rubber insert 25 between the hood 24 and base 11 insures an air tight seal therebetween. The top of the hood 24 is centrally apertured to receive the polisher 22 which is removably clamped to the hood by a threaded collar 26. The paper covered wire passes through an apertured disk 27 of rubber or other resilient material inserted between the polisher 22 and a cap 28 threaded upon the upper end of the polisher. The base wire enters the tubular shaft 10 through an apertured rubber disk 29 similar to the disk 27 and removably secured to the lower end of the shaft by a threaded cap 30 having a baffled chamber 31. The rubber disks 27 and 29 serve to facilitate the maintenance of a vacuum or partial vacuum within the hood 24 which is connected by a pipe 32 to suitable evacuating apparatus (not shown). To further facilitate the maintenance of the vacuum within the hood 24, the polisher 22 may be provided with a central annular chamber 33 formed with oppositely disposed baffles 34 and 35 and connected to the evacuating apparatus by a pipe 36.

During the operation of the serving mechanism 15, a vacuum or partial vacuum is maintained within the hood 24, whereby the atmospheric friction encountered by the material being served is eliminated or reduced to a minimum. Breakages of the material due to atmospheric friction are thus eliminated, thereby permitting the application of the material at speeds considerably higher than heretofore practicable. The efficiency of the apparatus is correspondingly increased, and the elimination of breakages of the covering material obviously results in an improved and more uniform product.

It is to be understood that the specific embodiment of the invention herein illustrated and described merely represents one useful application of the invention which is capable of numerous other applications within the scope of the appended claims.

What is claimed is:

1. In an apparatus for covering a core, a main chamber through which said core is adapted to pass, points of entrance and exit for said core in said main chamber, means located within said main chamber for applying a covering material to said core, and an auxiliary chamber at at least one of said points in said main chamber through which said core passes for preventing the passage of air into said main chamber and thereby maintaining controlled atmospheric conditions within said main chamber.

2. In an apparatus for covering a core, a main chamber through which said core is

adapted to pass, said main chamber comprising a supporting base and a removable hood, points of entrance and exit for said core in said main chamber, means located within said main chamber for applying a covering material to said core, and an auxiliary chamber at at least one of said points in said main chamber through which said core passes for preventing the passage of air into said main chamber and thereby maintaining controlled atmospheric conditions within said main chamber. 70

3. In an apparatus for covering a core, a main chamber through which said core is adapted to pass, points of entrance and exit for said core in said main chamber, means located within said main chamber for applying a covering material to said core, a hollow shaft associated with said covering means and through which said core is adapted to pass, and an auxiliary chamber at at least one of said points in said main chamber through which said core passes for preventing the passage of air into said main chamber and thereby maintaining controlled atmospheric conditions within said main chamber. 80

4. In an apparatus for covering a core, a main chamber through which said core is adapted to pass, points of entrance and exit for said core in said main chamber, means connecting said chamber with an atmosphere of reduced pressure, means located within said main chamber for applying a covering material to said core, an auxiliary chamber at at least one of said points in said main chamber through which said core passes and means connecting said auxiliary chamber with an atmosphere of reduced pressure for preventing the passage of air into said main chamber and thereby maintaining controlled atmospheric conditions within said main chamber. 95

5. In an apparatus for covering a core, a main chamber through which said core is adapted to pass, points of entrance and exit for said core in said main chamber, means located within said main chamber for applying a covering material to said core comprising a high speed rotatable head carrying a supply of said covering material around said core, and an auxiliary chamber at at least one of said points in said main chamber through which said core passes for preventing the passage of air into said main chamber and thereby maintaining controlled atmospheric conditions within said main chamber. 100

6. In an apparatus for covering a core, a main chamber through which said core is adapted to pass, points of entrance and exit for said core in said main chamber, means located within said main chamber for applying a covering material to said core comprising a high speed rotatable head carrying a supply of the covering material around said core, a hollow shaft for driving said rotatable head 110

115

120

125

130

and through which said core is adapted to pass, an auxiliary chamber at one end of said hollow shaft, and a second auxiliary chamber at one of said points in said main chamber through which said core passes for preventing the passage of air into said main chamber and thereby maintaining controlled atmospheric conditions within said main chamber.

In witness whereof, I hereunto subscribe my name this 2nd day of Feb. A. D., 1931.

JOHN R. SHEA.
